(57) **CLAIM**

The ornamental design for a wind resistant modular ISO building, as shown and described.

DESCRIPTION

FIG. 1 is a top perspective view of a wind resistant modular ISO building showing our new design;

FIG. 2 is a front view of the wind resistant modular ISO building;

FIG. 3 is a left side view of the wind resistant modular ISO building, the right side view being identical thereto; and, FIG. 4 is a top plan view of the wind resistant modular ISO building.

The broken lines shown in the drawings illustrate portions of the wind resistant modular ISO building that forms no part of the claimed invention.
